DESIGN FOR A SHOE

Andre Perugia, Paris, France

Application September 22, 1934, Serial No. 53,366

Term of patent 3½ years

To all whom it may concern:

Be it known that I, ANDRE PERUGIA, a citizen of the Kingdom of Italy, residing in Paris, France, have invented a new, original, and ornamental Design for a Shoe, of which the following is a specification, reference being had to the accompanying drawing, forming part thereof.

Fig. 2 is a front perspective view of the shoe.

I claim:

The ornamental design for a shoe, as shown.

ANDRE PERUGIA.
